FUR STORAGE APPLIANCE
Joan Gilliam Ramey, Skokie, Ill.
(512 Whitegate Lane, Wayzata, Minn.)
Filed Sept. 5, 1958, Ser. No. 759,214
11 Claims. (Cl. 62—261)

The present invention relates to a garment storage appliance, and in particular to a device which is adapted for the storage and preservation of fur garments. Fur storage is a widespread practice of business establishments and is generally done by cold storage or a type of air conditioning. These systems are efficient for large vault areas; however, there is no known device for maintaining furs in small quantities in a special appliance which will keep them at optimum temperature and humidity levels. There is an obvious advantage to a fur owner in having her fur garments readily available at all times and stored under optimum conditions on a full-time basis.

Four embodiments of the invention are disclosed in detail herein involving modifications in a basic design. It is to be understood, however, that the inventive idea may be carried out in other ways. This application is therefore not to be limited to the precise details shown, but is intended to cover all variations and modifications thereof falling within the spirit of the invention as defined in the scope of the appended claims.

From a practical point of view, the size of the appliance is limited by economic and space available factors. In most cases, the appliance will be of a size convenient to accommodate three fur wraps, such as coats, but it can also be considerably smaller and accommodate smaller pieces or folded garments, or larger to accommodate several additional garments.

In the past, fur garments have had to be either stored with a commercial firm or left to the possibility of moth damage, the drying out of the natural oils (which causes the skins to crack), and the collection of dirt and dust in the pores. Furs cannot have the natural oils replaced and are of value only so long as they remain supple and retain their natural oils.

It is the prime object of the present invention to provide a novel fur storage appliance simple in construction, compact in size, and light in weight so as to be particularly adapted for use with a small quantity of finished fur garments and probably for use in a home. (It, of course, could be used to store garments other than fur such as cashmere, leather, etc.)

A still further object of the invention is to provide a novel fur storage appliance which provides convenient access directly to the fur storage compartment thereof, which employs economical and readily available components, and which may operate with the greatest efficiency.

Yet another object of the present invention is to provide a portable fur storage appliance which may be easily transported from place to place and which may be adapted for installation in various areas and positions.

Another object of the present invention is to provide a fur storage appliance having a storage area of size sufficient to accommodate finished fur pieces such as coats and the operating parts of which being placed in as convenient an arrangement as possible in relation to the storage area.

Yet another object of the present invention resides in the provision of a fur storage appliance comprising a basic storage unit which can be associated with a refrigerating mechanism in a number of different manners to provide manufacturing economy. (In the illustrated embodiments a standardized fur storage unit is shown mounted alternatively at the interior or exterior of a conven-

2

tional household refrigerator and as part of a separate appliance having an individual refrigeration system.)

A further object of the invention resides in the provision of a fur storage appliance which operates in a very efficient manner and which may be entirely self-contained.

Yet another object of the present invention is to devise such an appliance which will maintain a temperature of desired level to preserve the garments and will be insulated consistent with practical demands.

Yet another object resides in the provision of an appliance sealed to the extent that odors may not be transferred to the fur garments contained therein and so that there is a minimum leakage of cooled air.

15 And yet a final object of the present invention is to make provision for a device to contain materials which will control the moisture and absorb odors which may be present in the appliance.

Further objects and advantages of the invention will 20 become apparent as the following description proceeds, and the features of novelty which characterize the invention will be pointed out with particularity in the claims annexed to and forming a part of this specification. For 25 a complete understanding of this invention, reference may be had to the accompanying drawings in which:

FIGURE 1 is a perspective view of a first embodiment 30 of the invention wherein a fur storage unit is mounted at the interior of a conventional household refrigerator and utilizes the cooling system thereof;

35 FIGURE 2 is a side elevational view illustrating a second embodiment of the invention wherein the fur storage unit is disposed at the exterior of a conventional household refrigerator and utilizes parts of the cooling system of the refrigerator;

40 FIGURE 3 is a top plan view of the embodiment of FIGURE 2 with a portion of the top wall of the fur storage unit broken away to illustrate the disposition of the evaporator therein;

45 FIGURE 4 is a side elevational view of a fur storage 45 appliance having an integral refrigeration system to provide a readily portable unit with a portion of the access door broken away and with the front panel enclosing the refrigeration system removed;

FIGURE 5 is a diagrammatic illustration of an exemplary 50 refrigeration system of the adsorption type for use in the embodiments of FIGURES 4 and 6;

FIGURE 6 is a perspective view of a readily portable bag type fur storage appliance having a detachable cooling unit therefor and with portions broken away to show 55 internal construction;

FIGURE 7 is a fragmentary enlarged sectional view illustrating the manner of attachment of the support hang- 60 ers and rod to the storage unit;

FIGURE 8 is a fragmentary enlarged cross-sectional view illustrating the double-walled construction of the storage unit; and

FIGURE 9 is a fragmentary side elevational view illus- 65 trating a receptacle for the humidity and odor control elements at the interior of the fur storage unit.

60 In the embodiment of FIGURE 1, a fur storage unit 10 is disposed within the main interior space of a conventional household refrigerator designated by the reference numeral 11, having the usual access door 12. The storage unit 10 may correspond identically to the storage unit shown in FIGURES 2 and 3 and will be described in detail in connection with those figures. The unit may have walls of a solid impermeable material such as a plastic for preventing the transfer of odors from the food storage compartment of the refrigerator to the interior space of the fur storage unit.

70 The fur storage unit 10 is shown as being provided with

a door 13 having a handle 14. The door 13 may be provided with a suitable lock for safeguarding the contents of the unit.

The fur storage unit may be cooled by means of an evaporator therein connected with the refrigeration system of refrigerator 11 generally in the manner illustrated in FIGURE 3. The refrigeration system is normally located below the food storage space of the refrigerator and is coupled to a main evaporator in the food storage area.

In the embodiments of FIGURES 2 and 3, the fur storage unit 10 may be disposed at one side of refrigerator 11 and evaporator 15 of the unit may be coupled to the refrigerator system of refrigerator 11 and indicated by tubing 16 and 17. In this case, the storage unit will operate in accordance with the setting of the refrigerator to which it is attached. For example, tubing 16 may connect the inlet side of evaporator 15 with the inlet side of the main evaporator unit within refrigerator 11, and tubing 17 may connect the outlet side of evaporator 15 with the outlet side of the main evaporator within refrigerator 11.

As seen in FIGURE 2 evaporator 15 may comprise a sinuous tube disposed in a vertical plane at the rear of the fur storage space and may be separated from the fur storage space by means of a suitable guard or screen 18. For controlling the humidity level and absorbing odors, suitable materials such as silica gel and activated carbon may be inserted into a receptacle 19 mounted on rear wall 20 of the fur storage appliance. These materials may be mixed and contained in a single cloth bag if desired. By way of example, the receptacle 19 may have a solid bottom wall 19a and permeable front and side walls such as indicated at 19b, 19c and 19d. The permeable walls may for example be of wire mesh construction. The upper side indicated at 19e of the receptacle is open to receive the humidity and odor control materials. Preferably the open side of 19e of the receptacle is disposed directly beneath the evaporator 15 in such a manner that excess moisture condensing on the evaporator and falling therefrom will be caught and contained by the humidity control material in the receptacle 19.

Where small fur garments are also to be stored in the unit 10, a removable shelf such as indicated at 21 may be mounted at the lower portion of the storage space by means of brackets such as indicated at 22 and 23. Additional brackets may be provided as indicated at 24-27 where adjustment in the position of the shelf may be desired.

For supporting fur garments such as a coat in the storage space, a hanger bar 28 is mounted at the top of the storage space and may be secured to and extend transversely between side walls 29 and 30 generally at the midpoint of the depth dimension of the unit. The hanger bar is of course adapted to receive conventional garment hangers. While in the majority of cases an individual will have only one or two fur garments to be suspended from bar 28, the bar 28 is preferably of sufficient length to readily accommodate three fur wraps. With this width of storage space, a single storage unit will satisfy the needs of the majority of individual owners with maximum efficiency.

FIGURE 4 illustrates a storage unit 10 having an integral refrigeration system diagrammatically indicated at 31 contained within a housing 32 secured to the base of the unit. The housing has a removable front panel (not shown) for enclosing the front side of the housing. The housing may have louvers in the side walls thereof as indicated at 33.

The unit of FIGURE 4 has the same internal arrangement as shown in FIGURE 2, including evaporator or cooling element 15, receptacle 19, and hanger bar 28. Additionally, since the appliance of FIGURE 4 is to be a self-contained system, it is provided with suitable means for controlling operation of the refrigeration system. In

the illustrated embodiment, an on-off control 34 and a thermostatic control 35 are shown. The control 34 may be manually actuated to set the refrigeration system in operation and the control 35 may comprise a temperature sensing element in conjunction with an electric switch for maintaining the desired temperature level in the storage space. By way of example, the temperature sensing element may comprise an expansible thermosensitive bellows system which may be adjusted to open an electric switch when the temperature of the ambient air falls below a preselected level. The reference numeral 36 designates a conventional electrical cord for connection to the usual household outlet.

FIGURE 5 is a diagrammatic showing of the refrigeration system for the appliance of FIGURE 4 and shows one conductor of the cord 36 connecting to a terminal of on-off switch 34. The other terminal of on-off switch 34 is connected by conductor 37 to the electric switch of thermostat control 35. When the on-off switch and thermostatically controlled switch are closed, electric power is supplied to the refrigeration system. The system shown in FIGURE 5 is a conventional absorption refrigeration system well known in the art and has been illustrated as comprising a generator 40, a separating vessel 41, an analyzer 42, an air-cooled rectifier 43, a condenser 44, a cooling element or evaporator 15, a gas heat exchanger 45, a pressure chamber 46, an absorber 47, a condenser 48, and a liquid heat exchanger 50.

In the bag-type fur storage appliance of FIGURES 6-9, a bag storage unit 60 is provided with a series of hanger elements 61, 62, and 63 for suspending the unit from a rod 64 of the type normally found in home storage areas such as closets. The hanger elements may extend through receiving apertures in a top plate 65 which is preferably of rigid heat insulating material located within the bag unit immediately below the top wall 66 of the unit. The elongated straight portion of each of the hanger elements such as indicated at 61a in FIGURE 7 is vertically slidable with respect to the top plate 65 and top wall 66 and is fixed in the desired position by means of a spring clip 67.

As seen in FIGURES 6 and 8, the bag unit may comprise an outer bag 68 and an inner bag 69 preferably of flexible plastic sheet material having an insulating air space 70 therebetween. The inner bag may be secured at its upper margin to plate 65 which may be of rectangular configuration corresponding to the cross section of the inner bag. If desired, suitable means may be provided for spacing the top wall portion 66 of outer bag 68 above plate 65 to provide an insulating air space at the top of the unit.

For providing access to the interior bag, the inner and outer bags are provided with a vertical slit at front wall 71 which may be closed by a conventional zipper 72 having a slide fastener 73. For convenience the inner and outer bags may be secured together at the margins of the slit so that the single zipper provides an opening through both the inner and outer walls simultaneously.

For supporting fur garments within the storage space 60 of the unit, a support bar 74 may extend across the width of the bag beneath the top plate 65 and may be supported from the top plate by means of brackets such as indicated at 75 in FIGURE 7. The support bar may have the same length as described in connection with FIGURE 2.

FIGURE 9 illustrates a suitable receptacle 76 for receiving the humidity and odor control materials which may be those described in connection with FIGURE 2. The receptacle may comprise a pocket-like sheet of perforated plastic material secured to the inner surface of the inner bag 69.

For providing circulation of air within the storage space of the appliance of FIGURE 6, a partition wall 80 defines a vertical duct 81 at the rear of the storage unit 75 which extends for the height of the unit and communi-

cates with an aperture 82 in top wall 83a of the casing 83 of the cooling unit designated generally by the reference numeral 84. The wall 80 has an upper edge 80a terminating in spaced relation beneath the top plate 65 so as to provide communication between the storage space and the vertical duct 81, as indicated by arrow 85.

The partition wall 80 may be secured to side walls such as indicated at 69a of inner bag 69 at its opposite side edges. The lower edge of the partition wall 80 is disposed in alignment with and in close relation to upper edge 86a of evaporator plate 86. The plate 86 has a sinuous evaporator tube 87 thereon for cooling air in the space between the rear wall 83b and the evaporator plate 86 which extends across the width of the casing 83 between the opposite side walls thereof such as indicated at 83c.

The lower edge 86b of the evaporator plate 86 is spaced above the bottom wall of casing 83 to provide for the flow of cool air from the rear side of plate 86 under edge 86b and into a space between the front side of plate 86 and an insulating wall 88 which extends across the entire width of casing 83 between the upper and lower walls thereof. This flow of cool air produces a circulation in which relatively hot air enters vertical duct 81 at the top thereof, flows downwardly through aperture 82, past evaporator coil 87, under the lower edge 86b of evaporator plate 86, and upwardly through aperture 89 of top wall 83a and into the storage space of the storage unit. The apertures 82 and 89 are formed by means of a rectangular slot 83d in top wall 83a of casing 83 which receives a tongue-like portion 86c of evaporator plate 86.

For detachably securing the cooling unit 84 with the bag storage unit 60, the outer bag 68 is provided with a zipper runner 90 about its lower margin, and the casing 83 has a cooperating zipper runner 91 about the perimeter of top wall 83a so that the lower portion of the bag when secured to runner 91 is held in predetermined fixed rectangular configuration. A slide fastener is indicated at 92 for selectively interlocking runners 90 and 91 about the length thereof. Similarly, inner bag 69 is provided with a zipper runner (not shown) about its free lower margin for selective interlocking engagement with inner zipper runner 93 extending about the perimeter of top wall 83a of casing 83 inwardly of zipper runner 91. When the inner bag lower margin is secured to zipper runner 93, it is maintained in a predetermined rectangular configuration in substantially uniformly spaced relation within the outer bag 68 so as to provide an insulating air space of uniform extent about the sides of the storage space. It will be understood that a slide fastener, similar to fastener 92, will be associated with the zipper runners for the inner bag and that the inner bag may be secured to runner 93 prior to securing of the outer bag to runner 91.

A suitable refrigeration unit such as illustrated in FIGURE 5, may be housed within the casing 83 between the front wall 83e and the insulating wall 88. Insulating wall 88 serves to completely isolate this front space from the rear air circulation and cooling space. The front space may be provided with suitable means for promoting the dissipation of heat generated by the refrigeration unit and for example, side wall 83c and front wall 83e may be provided with louvers 94 and 95. A conventional electric power cord is indicated at 100 for supplying electric power to the refrigeration unit.

While several embodiments of the invention have been illustrated and described, the invention may obviously take additional forms and be variously applied within the scope of the following claims.

I claim as my invention:

1. As an article of manufacture, a fur storage appliance characterized by providing optimum and efficient fur storage and preservation conditions for fur garments and immediate access to by the owner thereof, said appliance comprising a bag-like structure having an interior

fur garment receiving space, said structure having an opening of vertical extent equal to at least a substantial proportion of the vertical extent of said fur garment receiving space for accommodating ready insertion and removal of a fur garment with respect thereto and having means providing for selective closure of said opening, means for mounting a humidity and odor controlling device in said interior storage space, fur garment supporting means carried by said appliance at the top of said fur garment receiving space for supporting fur garments in said space, suspension means at the top exterior of said structure for suspending said appliance in a larger storage space of an individual dwelling, and refrigeration means connected as a unit with said structure and operative to maintain said fur garment receiving space at an optimum fur storage temperature.

2. A fur storage appliance comprising a bag-type unit formed of a pliant substantially air tight material and having interior storage space, a refrigeration unit comprising a casing having an evaporator therein and having

means defining an air circulation passage extending in heat transfer relation to the evaporator, means securing the bottom edge of the bag unit to said casing, means defining a vertical air duct adjacent said storage space and communicating therewith at the top of said duct, and means affording communication between the lower end of said duct and said air circulation passage and between said air circulation passage and the lower end of said storage space.

3. A fur storage appliance comprising a bag-type unit formed of a pliant substantially air tight material and having an interior storage space, a refrigeration unit comprising a casing having an evaporator therein and having means defining an air circulation passage extending in heat transfer relation to the evaporator, means detachably securing the bottom edge of the bag unit to said casing, and means affording communication between said storage space and said air circulation passage for cooling said storage space.

4. As an article of manufacture, a fur storage appliance characterized by providing optimum and efficient fur storage and preservation conditions for fur garments and immediate access to by the owner thereof, said appliance comprising a bag-like structure formed of a double thickness of a pliant substantially air tight material having a substantially uniform air space of substantial extent therebetween, having an interior fur garment receiving space with an opening of vertical extent equal to at least a substantial proportion of the vertical extent of said fur garment receiving space, fur garment supporting means carried by said appliance at the top of said fur garment receiving space, a means for mounting a device to control humidity and odor in said interior storage space, suspension means at the top exterior of

5. As an article of manufacture, a fur storage appliance characterized by providing optimum and efficient fur storage and preservation conditions for fur garments and immediate access to by the owner thereof, said appliance comprising a bag-like structure having an interior fur garment receiving space, said structure having an opening of vertical extent of the fur garment receiving space for accommodating ready insertion and removal of a fur garment with respect thereto and having means providing selective closure of said opening, means for mounting a humidity and odor controlling device in said interior storage space, fur garment supporting means carried by said appliance at the top of said fur garment receiving space for supporting fur garments in said space, suspension means at the top exterior of said structure for suspending said appliance in a larger storage space of an individual dwelling, and refrigeration means connected as a unit with said structure for cooling air in the interior of said bag unit.

6. As an article of manufacture, a fur storage appliance characterized by providing optimum and efficient fur storage and preservation conditions for fur garments and immediate access to by the owner thereof, said appliance comprising a bag-like structure having an interior fur garment receiving space, said structure having an opening of vertical extent of the fur garment receiving space for accommodating ready insertion and removal of a fur garment with respect thereto and having means providing selective closure of said opening, means for mounting a humidity and odor controlling device in said interior storage space, fur garment supporting means carried by said appliance at the top of said fur garment receiving space for supporting fur garments in said space, suspension means at the top exterior of said structure for suspending said appliance in a larger storage space of an individual dwelling, and absorption refrigeration means

7. As an article of manufacture, a fur storage appliance characterized by providing optimum and efficient fur storage and preservation conditions for fur garments and immediate access to by the owner thereof, said appliance comprising a bag-like structure having an interior

7
connected as a unit with said structure and operative to maintain said fur garment receiving space at an optimum fur storage temperature.

6. As an article of manufacture, a fur storage appliance characterized by providing optimum and efficient fur storage and preservation conditions for fur garments and immediate access to by the owner thereof, said appliance comprising a bag-like structure having an interior fur garment receiving space, fur garment supporting means carried by said appliance at the top of said fur garment receiving space, and means whereby said supporting means is adjustable for mounting said appliance with the bottom thereof resting on the floor of a larger storage space, and with a refrigeration means connected at the lower end of the bag-like structure. 10

7. A fur storage appliance comprising a bag-type unit formed of a pliant substantially air tight material having an interior storage space, the bag-type unit formed of a double thickness of a pliant substantially air tight material having a substantially uniform air space of substantial extent therebetween, having free lower margins, a casing having refrigeration means therein, and means for detachably securing said casing with the lower margins of said thicknesses of material comprising zipper means along each of said lower margins. 20

8. As an article of manufacture, a fur storage appliance comprising a bag-type unit formed of a substantially air tight material and having an interior storage space, a refrigeration unit enclosed in a casing, means affording communication between said storage space and said refrigeration unit for cooling said storage space, and means detachably securing said refrigeration unit to said bag unit. 30

9. As an article of manufacture, a fur storage ap-

pliance comprising a bag-type unit having an interior storage space, and a refrigeration means enclosed in a casing, means securing the bag unit to said casing, and means affording communication between said bag unit and said refrigeration means.

10. As an article of manufacture, a fur storage appliance comprising a bag-type unit formed of a pliant substantially air tight material having an interior storage space, free lower margins, a casing having refrigeration means therein, and means for detachably securing said casing with the lower margins of said material. 15

11. A fur storage appliance comprising a bag-type unit formed of a pliant substantially air tight material having an interior storage space, the bag-type unit formed of a double thickness of a pliant substantially air tight material having a substantially uniform air space of substantial extent therebetween, having free lower margins, a casing having refrigeration means therein, and means for detachably securing said casing with the lower margins of said thicknesses of material along each of said lower margins. 20
